UNITED STATES PATENT OFFICE.

FRANCIS ROBERT BAKER, OF BIRMINGHAM, COUNTY OF WARWICK,
ENGLAND, ASSIGNOR TO JOEL CADBURY, OF SAME PLACE.

GLOVE-FASTENER.

SPECIFICATION forming part of Letters Patent No. 340,852, dated April 27, 1886.

Application filed July 21, 1885. Serial No. 172,536. (No model.) Patented in England March 21, 1885, No. 3,635; in France June 23, 1885, No. 157,071, and in Germany July 9, 1885, No. 34,194.

To all whom it may concern:

Be it known that I, FRANCIS ROBERT BAKER, a subject of the Queen of Great Britain, and residing at Birmingham, in the county of 5 Warwick, England, engineer, have invented certain Improvements in Glove and other Like Fasteners, (for which I have made application for Letters Patent in Great Britain, No. 3,635, dated the 21st day of March, 1885; in France, 10 dated June 23, 1885, No. 157,071, and in Germany July 9, 1885, No. 34,194,) of which the following is a specification.

My invention relates to a new or improved fastener for gloves, boots and shoes, stays, garters, and for other like purposes; and my said invention consists, essentially, of a stud or hollow stem with a movable top which lies coincident with the said stem when unfastened, but eccentric to it when fastened, by the overhanging edge of the movable top, when in the last-named position, covering or overlapping the edges of an eyelet or button-hole on the other part of a glove or other object to be fastened.

25 I will describe my invention in connection with a glove-fastener.

Figure 1 is a glove provided with a fastener constructed according to my invention. Fig. 2 is the fastener upon a larger scale, with the 30 parts unfastened. This view shows the eyelet encircling the neck of the stem of the fastener. Fig. 3 is a like view as Fig. 2, but fastened—that is, the movable top has been moved or pressed eccentric to the stem, the eccentricity 35 of which prevents the one part of the glove from becoming disconnected from the other part. Fig. 4 is an edge view of Fig. 2, and Fig. 5 is a vertical section of Fig. 4. Fig. 6 is a plan of the under side of Fig. 5. Fig. 7 is a side elevation of Fig. 3 when the parts are represented in the positions as indicated in the said figure. Fig. 8 is a part vertical section of Fig. 7. Fig. 9 is an under side view of Fig. 7. Fig. 10 is a separate view of the movable top and 45 its depending stem. Fig. 11 is a plan of the box-stem of the fastener. Fig. 12 is the spring for retaining the movable head either in its open or in its closed position. In Fig. 13 the head,

instead of sliding, turns upon an eccentric pin or axis, in order to obtain the necessary lap. 50 This said view, Fig. 13, shows the fastener closed, and Fig. 14 the fastener opened. Fig. 15 is a transverse section of Fig. 13.

a is a box-stem or the body of the fastener, provided at its lower end with an attachment 55 flange, *a*², and spikes *a*³. The latter are for the purpose of securing the fastener to the glove.

b is a movable head or top, which is permanently or inseparably connected to the shell *a*, and which slides laterally across the top of the 60 said box-stem, so as to make the stem and head eccentric or concentric when fastened or unfastened. The said sliding head *b* has a depending stalk or rod, *b*², working within a slot, *a*⁴, of the box-stem *a*.

c is a spring of a semicircular form, and provided with curved arms *c*² *c*³, by which the head is retained in the two positions, fastened and unfastened—that is, the arm or turned ends *c*² *c*³ of the spring *c* form yielding incline planes which press upon opposite sides of the hanging rod *b*². Thus, when the head is concentric with its stem or body, as in Figs. 2 and 4, the rod or stalk *b*² is upon one side of the inclines, and when eccentric, as in Fig. 3, 75 the stalk or stem is upon the other side of the inclines, as best seen in Fig. 9.

*b*³ is a collar on the rod or stem for keeping the spring to its bearing.

d is an eyelet on the part A of the glove, 80 while the fastener is attached upon the other part, B.

To fasten the glove, pass the eyelet *d* over the head *b*, and onto the neck of the box-stem *a*, on the parts being concentric, as in Fig. 2, 85 and when in this position the head *b* is made eccentric with the stem *a* by sliding the said head into the position as represented in Fig. 3—that is, the head *b* has been made to overhang or overlap the eyelet or button-hole, and 90 so thereby effectually and securely fasten the two parts of the glove together. To unfasten the glove, slide the head *b* back to its former position until it and its box-stem become coincident, and when in this position the eyelet 95 can be withdrawn and the glove unfastened.

Fig. 13 represents a modification, where the overlapping of the edges is effected by the head turning upon an eccentric joint instead of sliding. *b* is the head, *a* is the box-stem, and *c* is the center upon which the head *b* turns. The depending stem *b*² has flats *b*⁴, upon which the flat spring *c* bears. To fasten a glove, pass the eyelet, as before, over the parts when concentric, as in Fig. 13, then turn the head *b* 5 slightly outward upon its center *c*, when the said head is made to overlap and become eccentric, as shown in Fig. 14.

Having fully described my invention, what I desire to claim and secure by Letters Patent 10 is—

The combination, in a glove or other like fastener, of a fixed box-like stem or body, *a*, a movable head, *b*, eccentrically adjustable with reference to said body, a spring which bears upon the stalk or stem *b*² of said head, and an eyelet, substantially as described. 20

Signed this 25th day of June, 1885.

FRANCIS ROBERT BAKER.
